UNITED STATES PATENT OFFICE.

ROBERT E. JACKSON, OF VICTORIA, VIRGINIA.

LOCOMOTIVE-WASHING APPARATUS.

1,137,626.

Specification of Letters Patent. Patented Apr. 27, 1915.

Application filed April 18, 1914. Serial No. 832,777.

To all whom it may concern:

Be it known that I, ROBERT E. JACKSON, a citizen of the United States, residing at Victoria, in the county of Lunenburg and State of Virginia, have invented new and useful Improvements in Locomotive-Washing Apparatus, of which the following is a specification.

My present invention pertains to the washing of locomotives and other vehicles and machines; and it contemplates the provision of a washing apparatus constructed with a view to using to advantage a low-grade oil commingled with hot water, the use of the oil with the water being materially advantageous, since it contributes to the cleansing of the paint on the locomotive or other machine without bleaching or otherwise deteriorating the paint.

With the foregoing in mind the invention will be fully understood from the following description and claim when the same are read in connection with the drawing, accompanying and forming part of this specification, in which the figure is a broken view partly in elevation and partly in section, illustrating the apparatus constituting the best practical embodiment of my invention that I have as yet devised.

Referring by numeral to the said drawing: 1 is a tank designed to contain a low-grade oil, such as crude oil or fuel oil. The said tank is provided at 2 with a filling funnel, and the conduit 3 intermediate said funnel and the tank is equipped with a cut-off valve 4 which is designed to be closed after the tank is charged with oil. I also prefer to provide the tank 1 with a glass gage 5 to enable the attendant to perceive the height of oil in the tank. This gage, however, is not essential to the proper operation of the apparatus, and it may therefore be omitted, if desired, without affecting my invention.

6 is a pipe designed to be connected at the end 7 with a pump or an injector for supplying hot water from a boiler or other suitable source of supply, under a proper head. The said pipe 6 is connected through 50 a pipe 8 and a pipe 9 with the bottom of the tank 1, and the pipe 8 is provided at its end remote from the pipe 6 with a drain cock 10, to facilitate cleaning of the tank 1, when the same is necessary. During the 55 operation of my apparatus, the said drain cock 10 is closed.

The pipe 6 is connected at its forward end to a casing 11, and the said casing is designed to be connected to a hose 30 having a suitable nozzle (not shown). Within the 60 casing 11 the pipe 6 is provided with a discharge nozzle 13, and this latter is preferably, though not necessarily, provided with a circular series of minute apertures 14.

Connected at one end to the upper portion 65 of the tank 1 is an oil conduit or pipe 15, comparatively small in diameter. The lower end of the said pipe 15 leads at 16 into the wall of the nozzle 13, and communicates with the interior of the said nozzle. At a 70 suitable point in its length, and preferably adjacent the tank 1, the pipe 15 is provided with an oil-regulating valve 17, the said valve being provided on its stem with a pointer 18, designed to coöperate with an 75 arcuate graduated scale 19. By turning the valve 17 through the medium of the pointer 18, a definite proportion of oil is obtained, and the said proportion can be varied by adjusting the valve and depending on the 80 pointer in combination with the scale 19 to indicate the proportion of oil. At 20 the pipe 8 is provided with a non-return valve, arranged to open toward the tank 1.

In the practical operation of my novel apparatus, hot water under a suitable head is 85 forced through the pipe 6 in the direction indicated by arrow. A portion of the water will pass the valve 20 and enter the tank 1, and will displace the oil from the tank, and 90 force it through the pipe 15. The remainder of the water will pass throughout the length of the pipe 6, and at the nozzle 13 will take up and become commingled with the oil, and when the commingled oil and hot water 95 is forced through the hose 30 and against the locomotive or other machine to be washed, the painted parts of the machine will be thoroughly cleansed, and yet there will be no bleaching or other deterioration 100 of the paint.

While I have disclosed the preferred embodiment of my invention, it is to be understood that in the future practice of the invention such changes or modifications may 105 be made as do not involve departure from the scope of my appended claim.

Having described my invention, what I claim and desire to secure by Letters-Patent, is:

An apparatus for the purpose described, comprising an oil tank, a casing, a hose con-

nected with the forward end of said casing, a pipe adapted to be connected with means for supplying hot water under a proper head and connected with the rear end of the casing, said pipe having a contracted discharge in the form of a nozzle extending forwardly in said casing, a conduit intermediate the pipe and the tank and opening into the bottom of the tank; said conduit having a valved drain outlet, and a comparatively-small conduit for oil interposed between the tank and the casing and having

its discharge end extending into the casing and connected with the interior of the nozzle on the pipe at an intermediate point in ~~16~~ the length of said nozzle.

In testimony whereof I have hereunto set my hand in presence of two subscribing witnesses.

ROBERT E. JACKSON.
